UNITED STATES PATENT OFFICE

CARL LITTLEFIELD, OF BATTLE CREEK, MICHIGAN, ASSIGNOR TO BATTLE CREEK
BREAD WRAPPING MACHINE COMPANY, OF BATTLE CREEK, MICHIGAN

MECHANICAL MOVEMENT

Application filed October 9, 1926. Serial No. 140,575.

The main object of this invention is to provide a mechanical movement for imparting an irregular movement from a driving member having a regular movement.

5 Objects relating to details and economies of construction and operation of my invention will definitely appear from the detailed description to follow.

The invention is defined and pointed out in 10 the claims.

A structure which is a preferred embodiment of my invention is illustrated in the accompanying drawing, forming a part of this application, in which:

15 Fig. 1 is a side elevation of a mechanism embodying the features of my invention, the parts being shown mainly in conventional form.

Fig. 2 is a similar view with the parts in 20 another position.

In the drawing similar reference characters refer to similar parts throughout the several views.

In the accompanying drawing I have illustrated 25 my improvements as I have embodied the same in a wrapping machine, the part 1 representing a transfer plunger by means of which the articles are shifted from a feed conveyor to a wrapping mechanism. These 30 parts, however, are not shown as they form no part of my present invention.

2 represents a gear wheel connected to a suitable source of power and coacting with the gear 3 having a driving crank 4 thereon.

35 5 is a rockshaft having an arm 6 thereon connected to the driven member 1 by means of the link 7. The rockshaft 5 has a second arm 8 which is connected to the driving crank by a connecting rod consisting of the links 9 and 10, the links being pivotally connected at 40 11, the link 9 being connected to the crank by the wrist pin 12 while the link 10 is connected to the arm 8 by the pivot 13.

The link 9 is supported at its outer end by 45 the rocker arm 14 which is pivoted at 15 and connected to the link by the pivot 16.

In the embodiment illustrated the links and pivots and the rocker 14 are so proportioned and arranged that during a portion of 50 the stroke the pivot 11 swings in an arc of

which the pivot 13 is the axis, the result being that there is a dwell in the movement of the actuated rockshaft and consequently to the driven member operatively connected thereto. By this means the stroke may be 55 properly timed relative to other moving parts.

My improved mechanical movement is adapted for many uses where a movement of this character is desired. The parts are simple and economical in structure and assembling and capable of a very wide adaptation.

Having thus described my invention, what I claim as new and desire to secure by Letters Patent, is:

1. In a mechanical movement, the combination of a driving crank, a rockshaft provided with an arm, a pivotally mounted rocker arm having its swinging end disposed in the general direction of the rockshaft, a link connecting the swinging end of said rocker arm to said crank, and a second link pivotally connected to said arm on said rockshaft and to said first mentioned link at a point centrally between its connections to said driving crank and rocker arm and so that the pivot connecting said links moves during a part of each cycle of the crank in the arc of a circle of which the pivot connecting the second link to the rockshaft arm constitutes a center. 75

2. In a mechanical movement, the combination of a driving crank, a rockshaft provided with an arm, a pivotally mounted rocker arm disposed with its swinging end in the general direction of the rockshaft, and driving connections for said driving crank to said rockshaft comprising a link connected to said driving crank and to the swinging end of said rocker arm and a second link connected to said arm on said rockshaft and to said first mentioned link at a point centrally between its pivotal connections to the driving crank and rocker arm. 85

3. In a mechanical movement, the combination of a driving crank, an oscillatingly supported actuated member, a pivotally mounted rocker arm disposed with its swinging end in the general direction of the said actuated member, and driving connections for said crank to said actuated member comprising a 95 100

link pivotally connected to said crank and to said rocker arm and a second link pivotally connected to said actuated member and to the first mentioned link at a point intermediate the pivotal connections for said driving crank and rocker member and so that during a portion of its travel it moves in the arc of a circle centering in the pivot connecting the second link to the actuated member.

10 In witness whereof I have hereunto set my hand.

CARL LITTLEFIELD.
